(57) **CLAIM**

The ornamental design for a shoe as shown and described.

DESCRIPTION

FIG. 1 is a rear, right side perspective view of a shoe showing our new design;

FIG. 2 is a front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines shown in the FIGS. 1-7 are included for the purpose of illustrating portions of the shoe that form no part of the claimed design. The dot-dash-dot lines are unclaimed boundaries between the unclaimed interior of the footbed and the claimed portion of the exterior of the shoe and form no part of the claimed design.
